PUMP FEED OILCAN

Gustave Lidseen, Chicago, Ill.

Application April 29, 1943, Serial No. 484,993

3 Claims. (Cl. 221—51)

My invention relates to a pump feed oil can of the type in which, by the manipulation of a pump lever at the top of the can, oil is pumped from the can for flow under pressure through and out of the spout. In my Patent No. 1,542,896, dated June 23, 1925, I show a can of this type, and in general the object of the invention is to provide a more practical and more efficient operating mechanism for pump structure such as shown in my patent.

More in detail, one important object is to provide an arrangement in which the can handle or grip is secured to and extends from the can cover and provides a fulcrum seat for the thumb-operated pump lever.

A further object is to provide improved means for connecting the pump lever with the pump plunger.

A further important object is to provide an arrangement in which the pump lever has a passageway therethrough receiving the base of the spout structure to be guided thereby and to be held in proper fulcrum engagement with the handle.

Another important object is to provide an arrangement in which a pump rod extends through and is guided by the can cover and is connected at its outer end with the pump lever and at its inner end with the pump plunger.

Still another object is to provide improved means for preventing leakage of oil from the can to the exterior thereof along the pump rod.

Other and further important objects of the invention will be apparent from the disclosures in the specification and the accompanying drawing, in which drawing:

Figure 1 is a side elevation of my improved oil can;

Figure 2 is an enlarged diametral section of the can cover and upper part of the can body, showing the pump mechanism in normal position;

Figure 3 is a view like Figure 2 showing the pump lever depressed for pump operation and discharge of oil from the spout;

Figure 4 is a plan view of the cover structure; and

Figure 5 is an under side view of the cover.

The cover structure 10 is of sheet metal and has a number of helical extending flange segments 11 for engagement with flange segments 12 on the can body or container 13 for holding the can intimately against the sealing gasket 14 on the cover. Extending upwardly from the cover is the cylindrical housing 15 which may be an integral part of the cover and which at its upper

end has the contraction or neck 16 to which the lower end of the spout 17 is secured.

The handle or grip structure 18 for the can has its upper end 19 extending along the top of the cover and terminating in a collar 20 which receives the housing 15. The handle structure is secured to the cover as by welding, or riveting 21. Secured within the housing 15 on the cover is the inverted sheet metal cup 22 forming the cylinder for the cup-shaped plunger or piston 23 to which the oil feed pipe 24 is secured at its upper end, this pipe extending down to the bottom of the can adjacent the forward edge thereof, as shown on Figure 1, and at its lower end has the ball check valve 25. The upper wall of the cylinder 22 has the outlet port 26 normally closed by a valve ball 27 under pressure of a spring 28.

Extending diametrically across the top of the cover is the pump lever 29 which has the elliptical opening 30 for receiving the housing 15 above the handle collar 20. This pump lever is of sheet metal and has the surrounding stiffening and strengthening flange 31 which, adjacent to the opening 30, is extended downwardly to form ears 32 and 33 which are in fulcrum engagement with the upper edge of the collar 20 on the handle, the engagement of the extension 15 in the opening 30 holding the lever with the ears in such fulcrum engagement with the collar.

At its inner end the pump lever has the opening 34 for receiving the pump rod 35 which at its upper end has the abutment head 36 engageable by the pump lever. The rod extends down through a guide bushing 37 secured to the cover 10, as by riveting, this bushing being preferably of steel. A sealing gasket or packing 38 receives the rod above the bushing, a cap 39 on the bushing holding the packing in place against the bushing end. The head of the cap is preferably frustoconical so that when the cap is forced down on the bushing it will compress the packing intimately against the rod to seal against the escape of oil from the can body outwardly along the rod, the cap, after setting on the bushing, being held in position as by deflection of a part thereof into the side of the bushing, as indicated at 40.

Connected to the inner end of the pump rod 35 is the U-shaped bracket 41. The rod extends through the hole 42 in the bottom wall of the bracket so that the outer wall 43 of the bracket will engage the rod, the rod having notches 44 in its end for receiving a split washer 45 against which the bracket seats. Extending from the opposite side of the inner wall 46 of the bracket are opposed ears 47 and 48 which extend up

along the opposite sides of the discharge pipe 24, the ears at their upper ends being rounded for engagement with the bottom wall of the plunger 23. A compression spring 49 between the plunger and the head of the cylinder 22 tends to hold the plunger and the pipe 24 down for the engagement of the plunger bottom with the bracket ears 47 and 48 and with the head 36 of the pump rod against the top of the pump lever 29, as shown on Figure 2. When the pump lever is now swung down, the pump rod is raised to lift the bracket 41 for upward movement of the plunger in the cylinder 22. During such upward movement, the check valve 25 at the lower end of the pipe 24 will be closed by the oil pressure and oil will be forced out of the cylinder past the valve 27 and into and out of the spout 17 for application to the bearing or other structure to be oiled. Upon release of the pump lever, the spring 49 will return the plunger and the pipe 24 downwardly, the valve 27 being then closed by the spring 28 and the check valve 25 opening for reception of oil into the pipe 24 for refilling of the cylinder 22. The force with which oil is expelled from the nozzle depends upon the force of the pressure applied to the pump lever when pressed downwardly. Figure 3 shows the pump lever being depressed for outward shift of the plunger by the bracket 41, the intimate engagement of the outer wall 43 with the pump rod 35 holding the bracket against downward swing during outward shift thereby of the plunger.

The inlet end of the feed pipe 24 should be maintained at the front of the can body opposite the handle 18 so as to be kept immersed in oil. To prevent displacement of the pipe from this position, the plunger bottom is deflected outwardly to provide abutment beads 50 for the ends of the bracket ears 47 and 48, the engagement of these abutments with the ears limiting rotational displacement of the pipe to hold its inlet end in the proper position near the bottom and front of the can. The bracket ears at the opposite sides of the pipe 24 will hold the bracket against undue rotational movement on the pump rod. The frictional engagement of the outer wall 43 of the bracket against the pump rod will also assist in holding the bracket against rotational movement.

With the handle structure secured to and extending from the cover structure and the comparatively wide pump lever receiving the cover extension 15 to be guided thereby for fulcrum engagement with the handle structure, a strong assembly results which will protect the pump lever against displacement and will at all times guide the lever for efficient reciprocation of the pump rod for operation of the pump mechanism for discharge of oil from the spout. The pump rod by being guided by the bushing on the head and operating through the bracket 41 will insure axial operation of the plunger in the cylinder without binding, so that the oil discharge struc-

ture will operate easily and efficiently at all times.

I have shown a practical and efficient embodiment of my invention but I do not desire to be limited to the exact construction or engagement shown and described as changes and modifications may be made without departing from the scope of the invention.

I claim as my invention:

1. An oil can of the type described comprising a container for oil, a cover for said container having a housing extending upwardly therefrom, a spout extending from said housing, a pump structure within said housing for pumping oil from said container for discharge through said spout, a handle secured to said cover and having a collar receiving said housing, a pump rod extending through said cover for axial movement and having connection at its inner end with said pump structure, a pump lever extending diametrically across said cover and having an opening therethrough for receiving said housing and having fulcrum support on the upper edge of said collar, said lever being connected at one end with the outer end of said rod for movement of said rod for operation of said pump structure to discharge oil through said spout.

2. An oil can comprising a container for oil, a cover for said container having a housing extending upwardly therefrom, a spout extending upwardly from said housing, a pump structure within said housing for pumping oil from said container for discharge through said spout, a collar surrounding said housing, a pump rod extending through said cover for axial movement and having connection at its inner end with said pump structure, a pump lever extending diametrically across the cover and having an opening therethrough for receiving said housing above said collar and having ears depending from opposite sides thereof into engagement with the upper edge of said collar to support said lever for rocking movement, said lever being connected at one end to the outer end of said rod for movement of said rod for operation of the pump structure to discharge oil through said spout.

3. An oil can of the type described comprising a container for oil, a cover for said container having a housing extending upwardly therefrom, a spout extending upwardly from said housing, a pump structure within said housing for pumping oil from said container for discharge through said spout, a pump rod extending through said cover for axial movement and having connection at its inner end with said pump structure, a collar surrounding said housing, a pump lever extending diametrically across said cover along opposite sides of said housing and connected at one end to the outer end of said rod, said lever having depending ears engaging the upper edge of said collar whereby said lever may be rocked on said collar for operation of said rod and the pump structure.

GUSTAVE LIDSEEN.
